TELESCOPING PLUNGER HAMMER

William A. Douglass, 5251 Pattison Ave.,
St. Louis, Mo. 63110

Filed May 13, 1966, Ser. No. 2,284

Term of patent 14 years

(Cl. D54—13)

FIG. 1 is a side view of a telescoping plunger hammer, when fully extended, embodying my new design. The top element is shaded to show a cylindrical handle element, flat and unornamented on either undisclosed end.

FIG. 2 is a similar view of the hammer looking toward the side opposite to that shown in FIG. 1 and showing the hammer fully telescoped.

FIG. 3 is a top plan view of the hammer and showing it in a normal operating position as applied to an automobile top and windshield assembly as shown in broken lines for illustrative purposes only. The entire hammer is shown rotated about its axis 90° from the positions shown in FIGS. 1 and 2.

FIG. 4 is a transverse section on the line 4—4 of FIG. 2 and looking in the direction of the arrows.

FIG. 5 is a transverse section on the line 5—5 of FIG. 1 and looking in the direction of the arrows.

I claim:

The ornamental design for a telescoping plunger hammer, substantially as shown and described.
